UNITED STATES PATENT OFFICE.

HERBERT E. SPRING, OF FITCHBURG, MASSACHUSETTS, ASSIGNOR OF ONE-HALF TO
EMMONS CROCKER, OF FITCHBURG, MASSACHUSETTS.

SCREEN-PLATE HOLDER.

1,073,825.

Specification of Letters Patent.

Patented Sept. 23, 1913.

Application filed July 23, 1912. Serial No. 711,141.

To all whom it may concern:

Be it known that I, HERBERT E. SPRING, a citizen of the United States, residing at Fitchburg, in the county of Worcester and 5 State of Massachusetts, have invented certain new and useful Improvements in Screen-Plate Holders; and I do declare the following to be a full, clear, and exact description of the invention, such as will enable others 10 skilled in the art to which it appertains to make and use the same.

This invention relates to paper making, and more especially to the screens employed in machines of this class; and the object of 15 the same is to produce an improved screen plate holder in which no fastening screws pass through the screen plates and no screws need be removed when said plates are to be removed. This and other objects are accomplished by constructing the improved screen 20 plate holder in the manner hereinafter more fully described and claimed, and as shown in the drawings, wherein—

Figure 1 is a plan view of a screen constructed in accordance with this invention, partly broken away; and Fig. 2 is a side elevation thereof, also partly broken away; Fig. 3 is a cross section on the line 3—3 of Fig. 2; Fig. 4 is an enlarged cross section on 30 the line 4—4 of Fig. 1; and Fig. 5 is a section at right angles to the sectional line of Fig. 4; Fig. 6 is a perspective detail of the casting shown in section in Fig. 5 and which will be referred to hereinafter, this casting 35 being turned on its side in Fig. 6 to better illustrate the shape of its lower end; Fig. 7 is a perspective detail of one end and a portion of the center of one of the strips hereinafter described; and Fig. 8 is a fragmentary 40 detail in perspective of a portion of one of the cross bars, with a socket plate supported thereon; Fig. 9 is an enlarged section on about the line 9—9 of Fig. 1; and Fig. 10 is a section at right angles thereto on about 45 the line 10—10 of Fig. 9; Fig. 11 is a perspective detail of the wedge shown in side elevation in Fig. 9; Fig. 12 is a perspective detail illustrating one end of one of the endmost strips hereinafter described; and 50 Fig. 13 is a perspective detail illustrating the shape of each corner of each screen plate.

The frame of this improved screen comprises side bars 1 and end bars 2 connected at the corners of the frame in any suitable 55 way and preferably braced by corner strips

3, the strips being of metal and the bars preferably of wood, and the parts being of the desired proportions and sizes according to the dimensions of the screen to be built. I may here say that the screen is made up, as 60 usual, of a number of plates provided with slits or openings through which the pulp is strained in a manner not necessary to amplify in this specification but well known to those familiar with the art of paper making, 65 and it is the purpose of the present invention to provide special means for holding the screen plates within the frame in such manner that the joints between the edges of the plates where they abut, between the ends 70 of the plates where they come in contact with the side bars of the frame, and along the sides of the two endmost plates where they also come in contact with the frame, will be as nearly water-tight as possible; 75 and yet all parts are held in place without the necessity for the use of screws passing through any plate and which when employed need frequent adjustment, often permit leakage or accumulate rust, and are always the source of annoyance—all of which objections are overcome by the present invention. Each plate 4 will be rectangular and approximately one foot by four feet in dimensions, its body provided throughout 80 with a series of slits as indicated at 5; and the frame shown best in Fig. 1 is internally of a size to accommodate eight such plates 85 edge to edge and fitting within the frame as shown. 90

Across the interior of the frame against its end bars 2 are secured the endmost cross bars 6, and—when eight screens are mounted in the screen as shown—seven other cross bars extend across the frames between the 95 endmost bars 6. Of the seven, four are rather smaller than the remaining three, the smaller ones being numbered 7 in Fig. 2 and the larger ones 8, but all these cross bars have tenons 9 (see Fig. 5) entering suitable 100 sockets 10 in the side bars 1 of the frame. Secured to the outer faces of said side bars, as by screws 11 or otherwise, are upright plates 12 disposed opposite the narrower cross bars only, and each plate has a lip 13 projecting 105 into the socket 10 beneath the tenon 9, and just above said lip another screw 14 projecting through the side bar and into the end of the tenon to draw the cross bar into close contact with the side bar and the tenon into 110

the socket wherein it rests upon said lip. The tenons at the extremities of the larger cross bars simply enter sockets in the side bars 1 in a manner well known and not necessary to illustrate, although if preferred (and especially if the screen plates were of considerable width) I might employ the plates 12 and lips 13 opposite all the cross bars. The latter may well be of wood, and along the upper edge of each is disposed a metallic strip whose shape is best seen in Fig. 7. This strip has a flat body 15 provided on its upper face with a pair of converging ribs 16 leaving a dove-tailed groove 17 between them throughout the length of the strip; and in both ends of the latter are cut upright rectangular notches 18 for a purpose yet to appear. Depending from the flat body at one, or possibly more, points throughout its length is a projection T-shaped in side elevation and consisting of a shank 19 and a head 20; and let into the upper edge of the cross strip immediately beneath the same is a socket consisting of a metal plate 21 held on the cross bar by screws 22 or otherwise, and having across its body a T-shaped slot 23 of a size to receive the head and shank of the projection. It follows that when this strip is applied to the upper edge of the cross bar and its projection engaged with the slot in said socket, it is held from displacement, and by reason of the rectangular shape of the shank 19 fitting closely in the small rectangular mouth of the socket, the strip is held against getting out of alignment with the cross bar. I have not illustrated and do not propose to use this fastening device beneath the endmost strips which overlie the endmost cross bars 6, because other means are provided for holding these strips in place as will appear below. Each of these strips has the same flat body 25, excepting that it is not as wide as the body 15 and is not notched at its extremities, its upper face carries one of the ribs 26 which is oblique as best seen in Fig. 12, and its outer edge carries an upstanding flange 28 of substantially triangular cross section, whose outer face is flat as seen in this view and whose inner face is inclined so that between this inner face and the adjacent face of the rib 26 there exists a longitudinal groove 27. The screen plates are by preference exact duplicates of each other, and one corner of a plate is shown in Fig. 13. The plate 4 may have any approved form of body provided with the slits 5 above described, but its frame will by preference be solid as seen at 30, notched out at each corner as seen at 31, and provided along each side in its under face with a groove 32 of a shape to pass over and loosely engage one of said ribs 16 or 26 as seen in Figs. 4 and 9 (the groove 65 running out at its extremity into the notch

31 as shown in Fig. 13), and the edge of the plate frame 30 beveled or undercut as at 33 for a purpose yet to appear.

With this construction of screen plates, and of the frame and its cross bars with the reinforcing strips along the upper edge of the latter, I make use of the following devices for holding the screens in place: Extending along inside each side bar 1 of the frame is a locking strip 35, preferably of wood and having its extremities beveled as seen at 36 in Fig. 9; and seated in the lower edge of this strip is a strip 37 of packing which extends across the ends of the screen plates and rests upon their upper faces as seen in Figs. 4, 5 and 9. Against the beveled ends 36 of each strip stand wedges 38 (see Figs. 9 and 10) whose outer faces rest within the end bars 2 of the frame, whose lower ends project through the notches 31 in the endmost plate 4 and are beveled on their outer faces as seen at 39 in Fig. 11 so as to engage over the beveled inner faces of the flanges 28 of Fig. 12, and whose upper ends are pierced with threaded holes 40. Mounted within each corner of the frame is a lug 41 within which is swiveled a screw 42 whose threaded lower end engages one of said holes 40, and when the screw is turned the wedge may be moved downward so that its beveled inner face engaging the beveled end 36 of the locking strip holds the latter in position, whereas its beveled outer face at its lower end at 39 engaging the flange 28 presses the end strip downward upon the endmost cross bar 6 and outward against the end bar 2 of the frame in a manner which will be clear. The use of two such wedges against the opposite ends of each locking strip holds the latter in place within the frame.

At points opposite the several brackets 12, castings like those shown in Fig. 6 are mortised into the outer face of each locking strip as seen in Fig. 5. Each casting comprises an upright body 45 having a right angular hook 46 projecting inward from its upper end over the upper edge of the strip 35 with a lip 47 engaging the corner thereof as shown, and an inwardly projecting toe 48 at the lower end of said body 45 let into the lower edge of said strip 35 outside the packing 37. Each casting also carries a plug 50 depending from said toe and extending downward through the registering notches 31 in the corners of the meeting plates and through the notch 18 in the extremity of the strip at this point, whereby the plugs and casting, and with the latter the locking strip 35, are prevented from springing inward toward the center of the frame as might be possible if the locking strip were of wood and became warped. Finally the plate 12 carries a lug 51 projecting through the side rail of the frame and having a nut 130

52 at its inner end, and through this nut passes a screw 53 which bears upon the hook 46 so that when the screw is adjusted the entire casting and this portion of the locking strip are moved downward to press the packing 37 closely upon the upper faces of the meeting edges of the two screen plates at this point. As suggested above, it may be necessary to provide these devices at the 10 ends of every alternate cross bar only within the frame, although it might be possible to have them occur more or less frequently; but the use of these locking devices in connection with those at the corners of the 15 frame will reliably hold the locking strips in place, and when the strips are borne downward their packing strips 37 reliably hold the screen plates in place with their grooves 32 in engagement with the ribs 16 and 26 of the metallic strips which stand 20 along the upper edges of the cross bars of the frame.

The parts of this improved screen plate holder, being constructed as above described, 25 are assembled as follows: Assuming that the cross bars are fixed in position within the frame, the end strips of Fig. 12 are laid upon the endmost bars 6, and the intermediate strips of Fig. 7 are laid upon the other 30 strips and held thereon by the T-shaped projections 19 engaging the T-shaped sockets 23, then the screen plates 4 are brought into place and their grooves 32 engaged over the upstanding ribs 26 of the end strips 35 and the upstanding ribs 16 of the other 40 strips, and packing 55 interposed between the beveled edges 33 of the contiguous screen plates, next the locking strips 35 with their castings attached are brought into place and 45 inserted within the frame under the projecting nuts 52 of the lugs 51, then the wedges 38 are inserted against the ends 36 of said strips and pressed down as far as possible by hand and the swiveled screws 42 inserted through the lugs 41, and lastly the 50 other screws 53 are passed through said nuts 52 and the parts are ready for final assembly.

By screwing down the screws 42 the wedges 48 are run down behind the beveled 55 ends 36 of the strip 35 so that the latter are forced downward and clamped in place, and the beveled corners 39 of the wedges engaging the flanges 28 of the end strips draw the latter outward against the ends 2 of the frame, and cause their ribs 26 engaging the 60 grooves 32 of the endmost screen plates 4 to draw said plates toward the ends of the frame. This causes the grooves at the other or inner edges of the endmost strips to 65 tightly engage the ribs 16 on the adjacent cross bars in a manner which will be clear. Next by screwing down the screws 53, the locking strips 35 are forced downward and their packing strips 37 borne down upon the 70 ends of the screen plates throughout the

length of the series, and this holds said plates from rising and—as has been above explained—holds said locking strips from becoming warped, meanwhile compressing the packing strips 37 so as to prevent leakage over the ends of any screen plate. Now by giving the corner screws 42 their final movements the beveled corners 38 of the wedges 39 move the inmost strips outward as far as possible within the ends of the frame, 75 and tension is put onto all the screen plates so that, if the parts are properly arranged and have been assembled as described, leaks between the contiguous edges of the screen plates and between the outer edges of the 80 endmost plates and the inner faces of the end bars of the frame is prevented, and the entire screen is complete. When now it is desired to remove any screen plate, it is only necessary to reverse the operation above described and loosen up on all screws to an extent sufficient to permit the removal of the locking strips 35, after which any plate or 85 plates may be withdrawn for purposes of cleaning or repair.

I would make the packing strips 55 and 90 37 of rubber or rubber composition, wood, metal, or other material; and possibly renew them from time to time. As has been above suggested, the materials of which other 95 parts are composed are not essential.

Attention is directed to a feature best illustrated in Figs. 4 and 9. This is the fact that the groove 32 along each edge of every plate has parallel walls inclined at the same 100 angle as do the side walls of each rib 16 or 26 so that the latter may fit into the groove, but the groove is wider than the rib and in the final assembly of parts the straining apart of the endmost plates draws the 105 grooves of all plates into close engagement with all the ribs throughout all the series so that it is impossible for any plate to become displaced as long as this straining continues. Moreover, the use of the triangular packing 110 55 between the undercut edges 33 of the plates where they abut, complements said edges and produces in effect a dove-tailed rib between the contiguous grooves 32 in the two plates which fits into the dove-tailed 115 groove 17 in the strip. However, when a plate is to be removed and the tension is relaxed sufficiently to enable one endmost plate to be unhooked from the rib 26 along its outer edge, then the groove 32 along its inner edge can be unhooked from the rib 16 on the next strip and the plate removed; this strip can then be moved laterally over the cross bar supporting it—the shape of the engaging projection and socket permitting—so 120 that tension on the second plate is released and it in turn can be removed like the first. This process can be kept up throughout the length of the series of plates within the frame, or another operator might be remov- 125 130

ing the plates and working from the other end of the frame inward until the two operators met at the center. By the use of this detail of construction, in connection with 5 the others hereinbefore described, I am enabled to dispense with screws for holding the plates in place, and thus the engagement of the beveled walls of the grooves 32 and the ribs 16 and 26 is such that in effect there 10 are inter-engaging ribs along the under side of the plates and the upper side of the strips and their engagement is such that when the plates are strained apart it cannot be disrupted.

15 What is claimed as new is:—

1. In a screen plate holder, the combination with a frame, and strips across within the same, each strip having a pair of upstanding ribs converging toward each other; of the 20 screen plates having grooves in their lower faces along their side edges wider than but shaped to conform with said ribs, other strips across the frame near its end rails and each having a single rib to engage the outermost groove in the endmost plate, and means 25 for moving said endmost strips apart to strain all the plates horizontally for the purpose set forth.

2. In a screen plate holder, the combination 30 with a frame, and strips across within the same, each strip having a pair of upstanding ribs converging toward each other; of screen plates having undercut edges and grooves in their lower faces near said edges 35 shaped to conform with said ribs and disposed so that when in engagement therewith the upper corners of the edges are in contact, a packing between the undercut edges of contiguous plates, and means for straining 40 the plates apart.

3. In a screen plate holder, the combination 45 with a frame, and strips across within the same, each strip having a pair of upstanding ribs converging toward each other; of screen plates having undercut edges and grooves in their lower faces near said edges 50 shaped to conform with said ribs and disposed so that when in engagement therewith the upper corners of the edges are in contact, a packing between the undercut edges 55 of contiguous plates, other strips across the frame near its end rails and each having a single rib to engage the outermost groove in the endmost plate, and means for moving said endmost strips apart to strain all the plates horizontally for the purpose set forth.

4. In a screen plate holder, the combination 60 with a frame having cross bars therein and provided with sockets in their upper edges, strips overlying certain of said cross bars having projections engaging said sockets to permit each strip to slide laterally upon its cross bar, and a pair of upstanding ribs along each strip converging toward each 65 other; of a series of screen plates whereof

each has downwardly projecting ribs along both edges shaped to conform with the ribs on said strips, and means for moving the endmost plates apart to put all the plates under horizontal strain for the purpose set 70 forth.

5. In a screen plate holder, the combination with a frame having cross bars therein and provided with sockets in their upper edges, strips overlying certain of said cross bars having projections engaging said sockets to permit each strip to slide laterally upon its cross bar, and a pair of upstanding ribs along each strip converging toward each 75 other; of a series of screen plates whereof each has downwardly projecting ribs along both edges shaped to conform with the ribs on said strips, other strips across the frame near its end rails and each having a single rib to engage the outermost rib in the endmost plate, and means for moving said endmost strips apart to strain all the plates horizontally for the purpose set forth.

6. In a screen plate holder, the combination with a frame having cross bars 80 therein and provided with sockets in their upper edges, strips overlying certain of said cross bars having projections engaging said sockets to permit each strip to slide laterally upon its cross bar, and a pair of upstanding 85 ribs along each strip converging toward each other; of a series of screen plates whereof each has downwardly projecting ribs along both edges shaped to conform with the ribs on said strips, other strips across the frame near its end rails each having a single rib to engage the outermost ribs in the endmost 90 plates and an upstanding flange beveled on its inner face and flat on its outer face adjacent the inner face of said end rail, the 95 corners of the endmost plate being notched, locking strips extending along within the side rails of the frame and having beveled 100 ends, and wedges in the corners of the frame engaging said beveled ends and having their lower extremities projecting through the notches in the endmost plates and engaging the beveled face of the flanges on said endmost strips, all as and for the purpose set 105 forth.

7. In a screen plate holder, the combination with a frame, and strips across within the same, each strip having a pair of upstanding ribs converging toward each other; of a series of screen plates whereof each has downwardly projecting ribs along both edges shaped to conform with the ribs on said strips, other strips across the frame near its end rails each having a single rib to engage the outermost ribs in the endmost plates and an upstanding flange beveled on its inner face and flat on its outer face adjacent the inner face of said end rail, the 110 corners of the endmost plate being notched, locking strips extending along within the 115 side rails of the frame and having beveled ends, and wedges in the corners of the frame engaging said beveled ends and having their lower extremities projecting through the notches in the endmost plates and engaging the beveled face of the flanges on said endmost strips, all as and for the purpose set forth.

side rails of the frame and having beveled ends, and wedges in the corners of the frame engaging said beveled ends and having their lower extremities projecting through the 5 notches in the endmost plates and engaging the beveled face of the flanges on said endmost strips, all as and for the purpose set forth.

8. In a screen plate holder, the combination with a frame, strips across within the same, each strip having a pair of upstanding longitudinal ribs, other strips across the frame near its end rails and each having a single upstanding rib and an upstanding 10 beveled flange, and a series of screen plates whereof each has downwardly projecting ribs along both edges shaped to conform with the ribs on said strips, each plate being also notched at all four corners; of wedges 15 movably mounted in the corners of the frame, passing through the notches in the endmost plates, and engaging the flanges on the endmost strips, and plugs movably mounted on the side rails of the frame and 20 25 engaging the registering notches between the meeting edges of contiguous plates.

9. In a screen plate holder, the combination with a frame, strips across within the same, each strip having a pair of upstanding longitudinal ribs, other strips across the frame near its end rails and each having a single upstanding rib and an upstanding beveled flange, and a series of screen plates whereof each has downwardly projecting 30 35 ribs along both edges shaped to conform with the ribs on said strips, each plate being also notched at all four corners; of wedges movably mounted in the corners of the frame, passing through the notches in the 40 endmost plates, and engaging the flanges on the endmost strips, locking strips extending along within the side rails of the frame between said wedges, castings carried by said locking strips and each having a plug engaging a pair of registering notches between the contiguous edges of meeting plates, and means for passing said locking strips downward.

10. In a screen plate holder, the combination with a frame, strips across within the same, each strip having a pair of upstanding longitudinal ribs, other strips across the frame near its end rails and each having a single upstanding rib and an upstanding beveled flange, and a series of screen plates whereof each has downwardly projecting ribs along both edges shaped to conform with the ribs on said strips, each plate being also notched at all four corners; 50 55 60 of wedges movably mounted in the corners of the frame, passing through the notches in the endmost plates, and engaging the flanges on the endmost strips, locking strips extending along within the side rails of the frame, packing strips in the lower edges of

said locking strips adapted to make contact with the upper faces of said screen plates near the ends of the latter, plugs carried by said locking strips and adapted to pass through registering notches between the 70 meeting edges of contiguous plates, and means for bearing said locking strips and their packing strips downward.

11. In a screen plate holder, the combination with the frame, cross strips within the same having upstanding longitudinal ribs, and a series of screen plates each having depending ribs along its sides adapted to co-act with said upstanding ribs and each notched in all four corners; of means for spreading the endmost plates in said series apart so as to put all the plates under tension for the purpose set forth, locking strips extending along within the side rails of the frame, castings carried thereby opposite certain of said cross strips and each having a body connected with the locking strip, a plug depending from the lower end thereof and adapted to engage registering notches in the meeting edges of contiguous plates, 75 80 85 and a hook at the upper end of the body extending over the locking strip and provided with a lip overhanging its front face, nuts carried by the side rails of the frame, and screws adjustable through 90 95 said nuts and bearing downward on said hooks.

12. In a screen plate holder, the combination with the frame, cross strips within the same having upstanding longitudinal ribs, 100 and a series of screen plates each having depending ribs adapted to co-act with said upstanding ribs and each notched in all four corners; of means for spreading the endmost plates in said series apart so as to put all of the plates under tension for the purpose set forth, locking strips extending along within the side rails of the frame, castings carried thereby opposite certain of said cross strips and each having a body 105 connected with the locking strip, a plug depending from the lower end thereof and adapted to engage registering notches in the meeting edges of contiguous plates, and a hook at the upper end of the body extending over the locking strip and provided with a lip overhanging its front face, cross bars within the frame beneath said strips and having tenons at their extremities, the side rails having sockets receiving said tenons, 110 115 120 plates secured against the outer faces of said side rails and having lips projecting into said sockets beneath the tenons and lugs projecting through the rail and having nuts at their inner ends, and screws adjustable 125 through said nuts and bearing on said hooks for the purpose set forth.

13. In a screen plate holder, the combination with the frame, cross strips within the same, and a series of screen plates adapt- 130

ed to co-act with said strips, each plate being notched in its corners; of means for spreading apart the endmost plates in said series so as to put all of the plates under tension for the purpose set forth, locking strips within the side rails of the frame, castings opposite certain of said cross strips and each having a body connected with a locking strip, a plug depending from the lower end of the body and adapted to engage registering notches in contiguous plates, and a hook at the upper end; cross bars beneath said cross strips and having tenons at their extremities, the side rails

of the frame having sockets receiving said tenons, plates secured to the side rails and having lugs projecting through them and carrying nuts, and screws adjustable through said nuts and bearing on said hooks, substantially as described.

In testimony whereof I have hereunto set my hand in presence of two subscribing witnesses.
